UNITED STATES PATENT OFFICE.

HEINRICH HERRMANN, OF BERLIN, GERMANY, ASSIGNOR TO ELECTRICITATS-
GESELLSCHAFT "SANITAS" M. B. H., OF BERLIN, GERMANY.

ELECTRIC HEATER.

Application filed June 13, 1924. Serial No. 719,895.

To all whom it may concern:

Be it known that I, HEINRICH HERRMANN, a citizen of Germany, residing at Berlin, Germany, have invented certain new and useful Improvements in Electric Heaters, of which the following is a specification.

My invention relates to improvements in electric heaters and more particularly in heaters provided with a switch controlling the supply of electric energy to the resistance wires of the heater. In heaters, such as are now in use, the switch is disposed between the heater and a wall plug or other source of electric energy, and as it is thus attached to the wall plug the leads are frequently torn from the terminals by carelessly handling the heater. The object of the improvements is to avoid this drawback. With this and other objects in view my invention consists in disposing the switch separately from the leads connecting the heater with the current supply and to an independent cable connected with the heater, the switch being provided at the end of the said cable and having the leads connected to one side only. In this system the cable intermediate the heater and the wall plug is uninterrupted and smooth, so that it can be conveniently handled and rearranged when it is entangled. By thus connecting the switch to the end of a cable it has the character of an ordinary wall switch which can readily be handled by unexperienced attendants.

For the purpose of explaining the invention an example embodying the same has been shown in the accompanying drawing in which,

Fig. 1, is a plan view of the heater and associated parts, and

Fig. 2, is a diagrammatical view showing the electric connection.

In the example shown in the drawing the apparatus comprises a heating pad C, and a cable B connecting the pad to a suitable source of electric current such as a wall plug A. The heating pad is provided with two resistance wires w^1 and w^2 adapted to be connected to the source of electric energy by means of a switch E so that either only one of the resistance wires is connected to the plug, or that both are connected in shunt or in series, for producing different

heating effects. The switch E is connected to the end of a cable D attached to the pad at the side opposite to the cable B, and comprising four leads permitting the aforesaid connections of the resistance wires w^1 and w^2 , while the cable B consists of two leads. As shown in Fig. 1 the switch comprise two coaxial cylindrical members e and e' rotatable relatively to each other and one provided with terminals connected with the leads of the cable D, and the other enclosing the bridging members, as is known in the art.

In Fig. 2 I have shown the inner or operative parts of the switch in a diagrammatical way. At the side adjacent to the member e' the member e carries eight concentric terminals f, g, h, i, k, l, m and n, and the terminals k and l are connected with the terminal h, the terminal n is connected by a lead s with one of the pins a^1 of the plug A, and the terminals f and g are connected with each other and the second pin s^2 of the plug A by wires t^1 , t^2 and t. The terminal i is connected by a lead p with the resistance w^2 of the heating pad C, the terminal n is connected by a lead s with the resistance w^1 , and the terminal m is connected by a lead o with the other ends of the resistance w^1 and w^2 . The rotary switch member e' is provided with bridges q-q' and r-r' adapted to connect pairs of the terminals of the member e according to the position of the member e' either for switching in one of the resistances or connecting both in shunt or in series for producing different heating effects. The wires s and t are combined into the cable B and the wires s, t, o and p into the cable D.

I wish it to be understood that I do not limit myself to the type of the switch shown in the figures.

From the description it will be understood that no strain is exerted by the leads on the switch when displacing the heating pad, because the switch is not fixed in position by being connected to the plug A.

I claim:

1. An electric heater comprising a heating pad including two resistances, a duplex cable issuing from said pad and ending in a contact plug, a multiplex cable issuing from said pad and ending in a manifold

switch, the wires of the cables being connected with the contacts of the switch and in part with the resistances in the pad in such a manner that in the different positions of the switch one resistance only may be circuited or both resistances may be circuited in parallel or in series, or both resistances may be cut out.

2. An electric heater comprising a heating pad including two resistances, a duplex cable issuing from said pad and ending in a contact plug, a multiplex cable issuing from another point of said pad and end-

ing in a manifold switch, the wires of the cables being connected with the contacts of the switch and in part with the resistances in the pad in such a manner that in the different positions of the switch one resistance only may be circuited or both resistances may be circuited in parallel or in series, or both resistances may be cut out.

In testimony whereof I affix my signature in the presence of a witness.

HEINRICH HERRMANN.
